UNITED STATES PATENT OFFICE.

GEORGE E. LATHAM AND WILLIAM F. WHITEMAN, OF SAN FRANCISCO, CALIFORNIA.

HEAT-DISTRIBUTER.

1,861,795.

Specification of Letters Patent. Patented Dec. 7, 1920.

Application filed July 1, 1919. Serial No. 307,897.

To all whom it may concern:

Be it known that we, GEORGE E. LATHAM and WILLIAM F. WHITEMAN, citizens of the United States, residing at San Francisco, in the county of San Francisco, State of California, have invented a new and useful Heat-Distributer, of which the following is a specification in such full and clear terms as will enable those skilled in the art to construct and use the same.

This invention relates to a portable radiator an object of which is to provide a radiator which can be easily moved from place to place and connected with a source of electric supply for heating purposes.

Another object of the invention is to dispense with the use of the ordinary pipe system for steam radiators while at the same time, the advantage of the steam heated radiator is retained.

Another object of the invention is to provide a heating element which is capable of being easily applied to any standard form of radiator.

It will be understood by those skilled in the art that it is much easier to maintain a temperature not above a given maximum with the use of water than with any other commercial or practicable means; and it is therefore easier to heat a body of water without danger to the heating element than it is to permit the heating element to be overheated, as it is likely to be if exposed to the air; and it is also easier to increase the radiating surfaces with steam than in any other way, so that a special object of the invention lies in the provision of an electric heated water and steam radiator with means to prevent the escape from the radiator of more than a minimum amount of the steam, ordinarily no steam escaping at all.

Other objects of the invention will appear as the description proceeds.

An embodiment of the invention is shown in the accompanying drawings in which the same reference numeral is applied to the same portion throughout, but we are aware that there may be modifications thereof.

Figure 1 is a perspective view of the complete heating distributor as it appears when connected by a source of electric current supply.

Fig. 2 is a view partly in section of the radiator and the heating element.

Fig. 3 is a transverse sectional view of the heating element, and

Fig. 4 is a view partly in section of the connecting socket.

In the drawings, the numeral 1 indicates the radiator of a common form having a plurality of heating sections. This radiator is provided with a handle 2 which may be used to carry it from place to place, and it is ordinarily filled with water to the dotted line as indicated on the side of one of the sections of the radiator. There is a gage 3 which has a cap 4 at its upper end, which cap holds a spring 5 and ball 6 in place, the object being to provide a safety valve to prevent the possibility of the radiator being placed under too great a pressure from the heating coil at the bottom of the radiator. In the place usually occupied by the steam pipe, there is a threaded plug 7, which plug is provided with a hexagonal nut 8 to enable it to be screwed in place; while a gasket 9 prevents the leakage of water from the radiator. Threaded or otherwise secured in the plug 7 is a metal tube 10, within which is a porcelain rod 11 around which is a coil of resistance wire 12 for the purpose of heating the water in the radiator. The tube 11 is made of porcelain, and one end of the resistance wire passes through it, while the other end is wound around it; and said wires are fastened to the terminals 13 and 14 carried by a plug 15 secured to the plug 7 by means of a suitable screw as indicated at 16.

Any cable terminal as indicated at 17, 90 may be used for supplying the coil with current from the cable 18. In order to prevent the resistance wire 12 from being displaced or from coming into contact with the metal of the shell 10 a cement made of asbestos fire clay or other suitable compound is filled into the tube 10 around the rod 11 as indicated at 20.

In operation, the cable 18 is connected to its socket and is applied to the radiator 100 socket 15, whereupon the water in the radiator will be heated; and as the steam rises from the water, heat will be delivered from the several sections of the radiator.

Should the radiator be overheated and cause too high a pressure of steam therein, the steam will escape by raising the safety valve; thereby avoiding the danger of an

explosion, but ordinarily there is no escape of steam from the radiator whatever.

What we claim is as follows, but various modifications may be made in the construction shown in the drawings and above particularly described form, within the purview of our invention.

10 A portable heat distributer comprising a plurality of heating members connected at the bottom and adapted to contain water, a combination safety valve and gage connected with the heating members, a detach-

able heating element secured in one of the heater elements comprising a tubular member having a resistance wire therein, said 15 tubular member being secured to an internal and external threaded bushing and electric contacts for said heater attached to said bushing.

In testimony whereof we have hereunto 20 set our hands this 24th day of June, A. D. 1919.

GEORGE E. LATHAM.
WILLIAM F. WHITEMAN.
